UNITED STATES PATENT OFFICE.

FREDERICK L. CURFMAN, OF MARYVILLE, MISSOURI.

FOOT TOBOGGAN.

Application filed December 4, 1923. Serial No. 678,461.

To all whom it may concern:

Be it known that I, FREDERICK L. CURFMAN, a citizen of the United States of America, and resident of Maryville, county 5 of Nodaway, State of Missouri, have invented certain new and useful Improvements in and Relating to Foot Toboggans, of which the following is a specification.

This invention relates to certain improvements in foot toboggans; and the nature and objects of the invention will be readily recognized and understood by those skilled in the art to which it relates in the light of the following explanation and detailed description of the accompanying drawings illustrating what I at present consider to be the preferred embodiments or mechanical expressions of the invention from among various other forms, arrangements, combinations and constructions of which the invention 15 is capable within the spirit and scope thereof.

One of the primary objects of the invention is to provide a foot toboggan particularly adapted for use in sliding and coasting on thin or relatively shallow ice and snow, or over relatively soft surfaces such as presented by snow, which is so formed and designed as to present a minimum of contact 25 surface when used on ice or sleet, and in which lateral or side slippage is materially reduced and practically eliminated.

Another object of the invention is to provide a foot toboggan having the operating 35 or engaging face thereof designed to present a minimum of engaging surface when used on ice or sleet, and which engaging surface is so formed as to prevent the same cutting through or piercing relatively thin ice or sleet and contacting with a surface therebelow.

Another object of the invention is to provide a foot toboggan having the operating or engaging side or face thereof formed 45 with a series of spaced longitudinally extending ribs or corrugations thereon having smooth rounded outer side or edge portions which will engage and contact with an ice or sleet surface without cutting there-through and which will further function as guiding elements and reduce side or lateral slippage of the toboggan in use.

A further object of the invention is to

provide a foot toboggan for sliding and coasting on ice; snow and such like, formed 55 of a sheet or strip of material having a relatively flat longitudinally corrugated portion adapted to be strapped or otherwise fastened on the foot of a wearer, and so formed that the corrugations stiffen and strengthen the 60 same, with the corrugations on the upper side providing a foot engaging surface and those on the under or operating side forming a series of spaced longitudinally disposed sliding surface engaging members 65 which will function as guiding elements and reduce lateral or side slippage of the toboggan.

A further object of the invention is to provide as a new article of manufacture a 70 substantially one-piece sheet metal, or other sheet material, foot toboggan adapted to be fastened to the foot for sliding or coasting, which can be cheaply and efficiently stamped, pressed or otherwise suitably formed from 75 sheet material.

A further object of the invention is to provide a foot toboggan for sliding and coasting on ice, snow and such like, a pair 80 of which are adapted to be fastened to the feet of a wearer, which is so designed that a wearer can walk with a pair without material interference or discomfort, and without injury to a surface with which the toboggans may contact.

With the foregoing and various other objects and results in view, which other objects and results will be readily apparent to those skilled in or familiar with this art from the following description, the invention consists 90 in certain novel features in construction and in arrangements and combinations of elements, as will be more fully and particularly referred to and specified hereinafter.

Referring to the accompanying drawings: 95

Fig. 1 is a side elevation of a foot toboggan embodying the invention.

Fig. 2, is a top plan view of the toboggan of Fig. 1.

Fig. 3, is a detail fragmentary view in 100 section taken on the line 3—3 of Fig. 2.

Fig. 4, is a view in bottom plan of the rear or heel portion of the sliding or operating surface of the toboggan.

Fig. 5, is a vertical transverse section 105 taken on the line 5—5 of Fig. 2.

Fig. 6, is a detail fragmentary view in side elevation of a modified form of the front curved end of a toboggan.

Fig. 7, is a side elevation of a modified 5 form of a toboggan of the invention.

Fig. 8, is a detail section through a modified form of rear or heel receiving end of a toboggan, and heel fastening means.

Fig. 9, is a rear elevation of the form 10 of the invention of Fig. 8.

According to the illustrated embodiments and mechanical adaptations of the invention, which are disclosed and described here-with purely by way of example and not 15 of limitation for purposes of explaining the principles involved and various features of and results obtained by the invention, a foot toboggan embodies and is formed from a relatively flat elongated strip or length 20 of suitable sheet material 10, such as relatively thin sheet steel or the like, of a length and width to be attached in position over and covering the bottom of a shoe (foot) to present on the outer or under side thereof 25 a relatively wide substantially flat sliding and coasting surface. This strip or length of sheet material 10 is rounded or curved at the rear or heel end thereof and is formed with the vertically disposed heel receiving 30 and retaining flange 11, stamped, pressed or otherwise struck up therefrom, and having the spaced series of ears or lugs 12 extending from the upper edge thereof to which the means for securing the toboggan onto 35 the heel of a shoe are attached, as will be explained hereinafter. The forward or nose end of the strip 10 is bent and curved upwardly and extended a distance rearwardly thereabove to form the foot protecting 40 and toe receiving portion 14 at the forward or advancing end of the toboggan. Opposite side vertically disposed and aligned strap attaching ears or lugs 15 are formed on the strip 10 at the forward end thereof 45 a distance rearwardly from the curved front end portion 14 of the toboggan to receive suitable straps or other securing means for fastening the forward end of a toboggan to a shoe, as will be more fully described 50 hereinafter.

With the body of the toboggan formed in the foregoing manner from the relatively thin substantially flat single or one-piece strip or blank of sheet material 10, an extended relatively wide flat length or base portion 16 is provided from and between the rear or heel receiving end 11 to the forward rearwardly curved or bent end 14, which extended flat base portion 16 of the 60 toboggan is adapted to be fastened or secured in position on and covering the bottom of a shoe (not shown), with the lower or under face thereof providing the sliding and coasting surface and the upper face providing the shoe bottom or sole receiving

and engaging surface, as will be clear from the accompanying drawings. In accordance with the invention the lower or operating face of the base portion 16 of the toboggan is so formed as to reduce the contact surface thereof to a minimum when sliding or coasting on hard surfaces such as ice, and to provide a contact surface which will not readily cut through or pierce thin or shallow ice and snow, and which will further function to guide the toboggan and reduce side slippage to a minimum. 75

In the illustrated examples of one possible mechanical expression of a sliding or operating surface embodying the principles and 80 features of the invention, the extended flat base 16 is longitudinally corrugated from the rear end thereof at the heel receiving flange 11 to the forward end thereof at the start of the curved or bent portion 14, 85 to provide a series of substantially parallel longitudinally disposed alternate convex ribs or corrugations 17 and concave depressions or grooves 18 throughout the substantial length of the flat under or operating 90 face of the toboggan. Similarly, a series of corrugations 19 are presented on the upper shoe bottom engaging surface of the base 16 of the toboggan. The spaced ribs or corrugations 17 extending longitudinally 95 of the operating face of the toboggan are smooth convex and rounded surfaces which preferably taper off or merge at their forward ends into the forward curved or 100 bent end 14 of the toboggan at or above the plane of the base portion 16, and which terminate and are cut off abruptly at the rear ends thereof to form the vertically disposed ends 17a at the curved rear or heel 105 end of the toboggan, as will be clear by reference to the accompanying drawings. These ribs or corrugations 17 on the operating face of the toboggan thus form the major contact surface thereof in sliding or 110 coasting over hard surfaces such as ice, with a material reduction in the contact surface presented with respect to the width of the base 16. Further, the corrugations of the extended substantially flat base 16 formed of the relatively thin sheet material 115 strengthen and stiffen the base and maintain the same against bending or twisting in use. If desired or found expedient the corrugations can be continued in the rearwardly curved front end 14 of the toboggan to stiffen and strengthen the same, as will 120 be apparent.

The foot toboggan so formed is provided with suitable means for attaching and securing the same in position on and to a shoe (foot), and in the embodiment of the invention disclosed in Figs. 1 and 2, such means embodies a piece of leather or other suitable material 20 secured at the lower 125 end thereof to the ears or lugs 12 around 130

the flange 11 at the rear or heel end of the toboggan, by rivets or the like 21. The leather piece 20 in mounted position on the toboggan thus forms a vertically extending curved portion to receive the heel or rear end of a shoe, and at its upper opposite forward ends is formed to provide a strap 22 and buckle 23, respectively, for securing the toboggan onto the heel or rear portion of a shoe, the strap 22 adapted to extend over and across the shoe in the usual manner well understood in this art. To secure the forward or toe portion of the toboggan to a shoe, a strap or the like 24 is secured at one end to one of the forward lugs or ears 15, and the opposite ear 15 is provided with a short strap and buckle 25 adapted to receive the free end of the attaching strap 24 when the latter is in position extending over and across the toe or forward portion of a shoe.

In Fig. 7 of the drawings a modified construction of the invention is disclosed particularly adapted for use when it is desired to form the toboggan from thin sheet material which may not develop sufficient strength and rigidity in the base portion 16 of the toboggan from the corrugations thereof, as hereinbefore described. This form of the invention provides opposite side stiffening flanges 26, struck up or otherwise suitably formed along and throughout the length of the base portion 16 and extending vertically therefrom. In the illustrated example these stiffening flanges 26 are continuations of the heel receiving flange 11 at the rear end of the toboggan, and extend forwardly to and terminate at the curved front portion 14 of the toboggan. However, if desired to stiffen and strengthen the forward curved portion 14 of the toboggan, the side stiffening flanges 26 can be extended and continued on and around the opposite sides of this curved portion to form the stiffening flanges 27 disclosed in Fig. 6 of the accompanying drawings. By the use of such stiffening flanges in connection with the stiffening and strengthening from the corrugations in the base 16, a relatively thin sheet material can be utilized to form the toboggan having the requisite strength and rigidity.

Another possible construction and formation of the rear or heel receiving end of the toboggan is illustrated in Figs. 8 and 9 of the accompanying drawings. In this form of the invention the use of the leather heel piece 20 is done away with by extending the heel receiving flange upwardly the necessary distance to provide the integral curved heel plate 20'. Any suitable or desired attaching strap 22' is mounted on the plate 20' for securing the rear end of the toboggan to a shoe in the usual manner. In the example illustrated, this attaching strap 22' is secured

in position on the heel plate by passing the same through a strap retaining member 12', struck or stamped out from the body of the heel plate 20', as will be clear by reference to Figs. 8 and 9.

In operation and use a foot toboggan is secured onto the shoe (foot) of a wearer with the shoe resting upon and covered by the base portion 16, by means of the heel attaching strap 22 and the toe attaching or forward strap 24, in the usual manner familiar in this art. With the toboggan in mounted attached position on a shoe the lower or under side of the base 16 of the toboggan presents and forms a relatively wide substantially flat longitudinally corrugated sliding and coasting surface. In sliding over a relatively hard surface such as ice the longitudinal spaced ribs or corrugations 17 only engage or contact, so that the actual contact surface with respect to the width of the operating face of the toboggan is materially reduced by the corrugated formation. The ribs or corrugations 17 are smooth, convex or rounded surfaces with the result that in sliding or coasting over thin or shallow ice, sleet or snow, they will not cut therethrough and contact with the surface therebeneath. The provision of the spaced longitudinally disposed ribs or corrugations 17 on the sliding and coasting surface of the toboggan reduces lateral or side slippage, particularly in use on relatively soft surfaces such as presented by snow, so that the toboggan is in effect guided or maintained on the desired course in operation. The guiding effect of the ribs 17 is materially aided by the abrupt termination thereof at the rear or heel portion to form the ends 17a which are thus disposed at the portion of the toboggan receiving the greatest weight and tend to be maintained in contact with a surface over which sliding by the forward or toe end of the toboggan rocking or swinging upward.

The upwardly curved forward end 14 of the toboggan provides primarily a forward inclined under surface 14a which functions to press down and form a harder surface for the toboggan to slide over when coasting on snow, and secondarily forms a guard or protection for the shoe or foot of the wearer to prevent snow from being thrown upwardly over the toboggan. The forward end portion of the toboggan may take the form as indicated by dotted lines in Fig. 1, in which the forward portion 14' is bent upwardly from the plane of the base 16 to present a more gradual sloping or inclined under surface 14a, and is not bent and extended rearwardly over the base. This form presents less possibility of interference from the forward ends of the toboggans in use, than with the form presented by the rearwardly bent portion 14.

The corrugations 19 on the upper face of the toboggan base 16 form a shoe engaging surface which will tend to prevent slippage of the shoe thereon and provide an efficient 5 shoe gripping face. However, attention is directed to the fact that it is not desired to limit all features of the invention to the provision of a corrugated upper or shoe engaging surface, as the invention contemplates 10 plates and includes the formation of a foot toboggan having a smooth or otherwise formed surface with the longitudinally ribbed or corrugated sliding surfaces. Where the toboggan is stamped or otherwise formed 15 from relatively thin sheet material the base portion 16 is materially strengthened and stiffened by the corrugation thereof in the manner disclosed in the drawings to provide the upper corrugated shoe engaging surface 20 and the correspondingly corrugated lower sliding or operating surface.

From the foregoing it is seen that a foot toboggan of simple construction is provided which can be readily and cheaply formed 25 from a substantially one-piece blank of sheet material. With the toboggan of the invention presenting the relatively wide substantially flat sliding or operating surface, a wearer with a pair attached can 30 readily walk to and from a sliding or coasting surface without material hindrance or interference, and without injury to any surface over which he may walk, due to the rounded smooth surfaces presented by the 35 ribs or corrugations 17.

It is further evident that various changes, variations, substitutions and modifications might be resorted to without departing from the spirit and scope of my invention, and 40 hence I do not wish to limit myself to the exact and specific disclosures hereof.

Desiring to protect my invention in the broadest manner legally possible, what I claim is:

45 1. A foot toboggan, embodying a substantially flat longitudinally corrugated sliding surface providing a series of convex ribs thereon.

50 2. A foot toboggan, embodying a sliding surface formed with a series of longitudinally disposed convex ribs thereon and terminating at the rear portion of said surface to present vertically disposed end faces.

3. A foot toboggan, embodying a base

55 formed of corrugated sheet material to present a substantially flat, relatively wide corrugated sliding surface having a series of longitudinally disposed convex ribs thereon.

60 4. A foot toboggan, embodying a base portion formed of sheet material presenting a comparatively wide substantially flat sliding surface, and the said base portion corrugated to stiffen the same and provide a series of spaced longitudinally disposed convex ribs on said sliding surface.

65 5. As a new article of manufacture, a sheet metal foot toboggan, formed from a single blank of substantially flat sheet metal to provide a base portion having a longitudinally corrugated sliding surface.

70 6. As a new article of manufacture, a foot toboggan formed from sheet metal to provide a substantially flat comparatively wide base portion formed with a heel receiving portion at the rear end and upwardly bent 75 at the forward end to form a foot protecting portion, and the said base portion longitudinally corrugated to present a sliding surface having a series of spaced convex ribs thereon.

75 7. As a new article of manufacture, a foot toboggan formed from thin sheet metal to provide a substantially flat base portion having a heel receiving flange at the rear end thereof formed to secure attaching 80 means thereto, the forward end of said base bent upwardly to provide a foot protecting portion, opposite side ears for receiving an attaching strap at the forward portion of said base, and the said base portion longitudinally corrugated.

85 8. As a new article of manufacture, a sheet metal foot toboggan having a substantially flat, relatively wide longitudinally corrugated base portion with the upper face 90 thereof forming a non-slip foot engaging surface, and the lower face providing a sliding surface having a series of spaced ribs thereon.

90 9. As a new article of manufacture, a sheet metal foot toboggan having a substantially flat, relatively wide base portion longitudinally corrugated, and opposite side stiffening flanges formed from said base portion.

105 Signed at Maryville, Missouri, this 1 day of Dec., 1923.

FREDERICK L. CURFMAN.
